UNITED STATES PATENT OFFICE.

HANS HENRIK CHRISTIAN GRONDAHL, OF CHICAGO, ILLINOIS, ASSIGNOR TO WESTERN ELECTRIC COMPANY, INCORPORATED, OF NEW YORK, N. Y., A CORPORATION OF NEW YORK.

MATERIAL-TREATING APPARATUS.

Application filed July 31, 1926. Serial No. 126,167.

This invention relates to material treating apparatus, and more particularly to apparatus for conveying and quenching material for use in connection with the heat treatment thereof.

Various types of apparatus have been employed for the purpose of conveying materials through furnaces, ovens and the like and for subsequently conveying such materials into a bath of cooling or quenching fluid. Many of these conveying and quenching devices have been designed to handle particular types of materials. Thus, for example, to effectively handle such materials as large metallic sheets or large, shallow pans supporting material which must be subjected to a process of annealing in a furnace, the conveying and quenching apparatus to be employed subsequent to the annealing process must be particularly adapted to satisfactorily handle these materials. The position of the materials after they have been removed or conveyed away from the furnace and subsequently quenched must be such that a suitable carrier apparatus, such as the type disclosed in my copending application, Serial No. 126,168, filed July 31, 1926, may be conveniently employed to remove the materials from the conveyor.

The primary object of this invention is to facilitate and expedite the handling of materials subsequent to the heat treatment thereof.

In accordance with the general features of the invention, one embodiment thereof includes a plurality of endless conveyors, electrically driven and positioned adjacent the openings of an annealing furnace, which are adapted to withdraw annealed materials from the furnace and to convey these materials into a position for quenching. A clutch mechanism selectively operates certain of the conveyors and means is provided for positively preventing the shifting of the clutch elements while the conveyor driving mechanism is functionally operative. Thus the engagement or disengagement of the clutch mechanism can only be effected when the electrical source of power supply has been removed. Quenching or sprayer devices are associated with each conveyor and are adapted to be vertically adjusted and positioned for effectively spraying materials

which have been advanced into the proper position by the conveyors. Thereafter, the sprayer devices may be lowered to a position clear of the material and a carrier on a crane cable may be very conveniently employed to remove the materials from the conveyor.

These and other objects of the invention will be more apparent from the following detailed description and in connection with the accompanying drawings, wherein

Fig. 1 is a side elevational view of one embodiment of the improved conveying and quenching apparatus;

Fig. 2 is an end elevational view of the driving end of the apparatus shown in Fig. 1 disclosing an arrangement of the clutch mechanisms;

Fig. 3 is an enlarged elevational view of the clutch control mechanisms as shown in Fig. 2;

Fig. 4 is a side elevational view shown partly in section of the control mechanism disclosed in Fig. 3;

Fig. 5 is a fragmentary plan view disclosing one pair of conveyor devices with the clutch control mechanism removed to disclose parts otherwise hidden;

Fig. 6 is a vertical longitudinal sectional view taken on the line 6-6 of Fig. 5;

Fig. 7 is a transverse vertical sectional view of a pair of conveyor units taken on the line 7-7 of Fig. 6;

Fig. 8 is an enlarged detailed sectional view of the upper portion of the sprayer devices as shown in Fig. 7, and

Fig. 9 is a fragmentary detailed perspective view disclosing a stack of metallic sheets supported by a conveyor tray linked to a conveyor chain.

Referring now to the drawings wherein like numerals have been used to designate similar parts throughout the various figures it will be observed that the apparatus includes a plurality of conveyor units denoted generally by the numeral 10 comprising upright frames 11 which are mounted on the floor of a pit 12 which is provided with a screened covering or floor 14. The upper portions of the frames 11 extend upwardly through the screened floor 14 and at their upper ends support two pairs of oppositely disposed and spaced supports or channels 15. The innermost channels 15 support a pair of parallel, angular guides 16 (Fig. 7)

which serve as a sliding support for a plurality of spaced inserts 18 which traverse and are secured to links 19 of conveyor chains 20. These conveyor chains 20 reach 5 between sprockets 22 which are mounted on a shaft 23 at the driving end of the apparatus (Fig. 6) and sprockets 24 (Fig. 1) suitably mounted at the opposite end of the apparatus. Positioned medially of the 10 frames 11 directly beneath the guides 16 are a pair of channel members 26 (Fig. 7) which function similarly to the guides 16 and serve to support the inserts 18 in the lower reach of the conveyor chain 20. It will be clear 15 that the guides 16 and the channel members 26 serve to prevent sagging of the conveyor chain 20 and likewise serve to retain and guide the chain in its predetermined position.

20 The driving mechanism for the conveyor chain 20 includes an electric motor 27 which is suitably mounted within a pit 28 and forms a part of an electrical circuit 29 shown in Fig. 3. This motor 27 transmits power to 25 a shaft 30 (Fig. 5) through the medium of suitable speed reduction gears and the shaft is connected with a clutch shaft 31 by means of a sprocket chain 32. The clutch shaft is mounted at its ends in bearing members 34 (Fig. 2) within the pit 28 and revolvably mounted upon the shaft 31 adjacent each of the bearing members 34 is a sprocket 35. The sprockets 35 are operatively connected 30 with the shaft 23 by means of suitable chains 38. These sprockets 35 are formed integral with a clutch member 36 which are adapted 35 to be engaged by companion clutch members 37 keyed to and slidably mounted upon the shaft 31. Spaced upright bearing members 39 serve as additional bearing supports for 40 the clutch shaft 31 and at their upper ends slidably support a shifter rod 40 which is connected at each end to the slidable clutch members 37 by means of suitable forked 45 members 42 depending therefrom. The shifter rod 40 is adapted to be reciprocated by means of a vertically disposed control lever 43 which is pivoted at 45 within an upright control support 46 and is connected 50 at its lower extremity with the shifter rod 40 by means of a link 47.

At the upper end of the central support 46 is a clutch control mechanism denoted 55 generally by the numeral 49 (Figs. 2, 3, and 4). This clutch control mechanism 49 comprises a screw 50 threaded within a suitable bearing 51 provided at the upper extremity of the support 46. One end of the screw 50 terminates in a locking pin 53 while the other end of the screw supports a hand 60 wheel 54 secured thereto. When the hand wheel 54 is in the position shown in Fig. 4 with its inner face abutting the end of the bearing 51, the lock pin 53 of the screw 50 65 will project or lie within the path of the

control lever 43. Thus when the lever is in its normal vertical or neutral position the lock pin 53 will project through an opening provided in the lever 43 and the lever cannot be shifted until the lock pin has been retracted. Likewise when the lever occupies its shifted position, it cannot be moved until the pin is retracted.

Immediately beneath the hand wheel 54 is a housing 56 which is suitably secured to the control support 46 and serves to enclose a conventional double push button electrical switch 57 which is connected within the circuit 29. A hinged cover plate 59 having a cam surface 60 provided at the upper end thereof is adapted to be swung into and out of covering relationship with respect to the face of the switch 57. A pin 61 carried by the cover 59 is adapted to engage the lower button of the switch 57 when said cover member is moved to its covering position as shown in Figs. 2, 3, and 4. The engagement of the pin 61 with the lower button of the switch 57 which is in series with the electrical circuit 29 containing the motor 27 causes the opening of the circuit and in order to reclose the circuit the cover 59 must be swung open so as to render possible the manual operation of the upper button of the switch 57. Pivoted at the point 63 immediately above one corner of the cover 59 (Fig. 3) is a latch 64, the upper surface of which is curved so as to permit the hand wheel 54 to be moved outwardly away from the bearing member 51 when the latch is in its lowermost position. When the hand wheel 54 is in the position shown in Fig. 4 the latch 64 is free to be moved upwardly and thus when the cover 59 is swung outwardly by grasping a knob 65 provided thereon, the cam surface 60 will engage with the underside of the latch 64 and cause said latch to be urged upwardly. However, when the hand wheel is moved to a position superimposing the latch 64, it will be impossible to swing the cover 59 outwardly by reason of the engagement of its cam surface 69 with the latch 64. In this connection it is also to be observed that the cover 59 must be completely closed and the latch 64 115 completely lowered in order to permit the hand wheel 54 to retract the pin 53.

From the foregoing it will be clear that by means of this control mechanism 49 the control lever 43 can never be operated while the motor 27 is functionally operative or in other words the control lever 43 can only be operated when the lock pin is in its retracted position. This condition can only exist when the cover 59 occupies the position shown in Figs. 3 and 4 and while it occupies this position the electrical source of power will be cut off. It will be clear that the hand wheel 54 can never be withdrawn when the cover 59 is swung away 130

from the switch 57. The latch 64 not only serves to prevent the actuation of the cover 59, but also serves to prevent the outward movement of the hand wheel 54 when the cover is swung open. The importance of this construction will be more readily appreciated when it is understood that this apparatus is to be driven by a motor capable of starting under full load conditions without the use of compensators or other forms of electrical motor starting devices. For this reason it is necessary that some means be provided to prevent the actuation of the clutch mechanism while the motor is functionally operative.

In parallelism with the side of each conveyor unit 10 are quenching or spraying devices 67 which comprise horizontal pipes 68 having a plurality of perforations 69 (Fig. 8) formed therein. These pipes 68 are slidably mounted at spaced intervals by means of vertical guide supports 71 and are provided with an intake coupling 72 which is connected with a suitable source of water supply (not shown) by means of a suitable valve 73 (Fig. 6). The pipes 68 may be readily raised and lowered by the manipulation of a crank 75, which when rotated, operates capstans 76. These capstans 76 are connected with the lower ends of the supports 71 by means of suitable cables 77 which pass over pulleys 79 mounted at the side of the conveyor units 10. To facilitate the raising of the pipes 68 counter-weights 80 are provided which tend to rotate the pulleys 79 over which the cables 77 pass. From the disclosure it will be apparent that the operation of the crank 79 will cause the raising or lowering of two sets of spraying devices 67.

In the operation of the apparatus material such as metallic sheets 81 as shown in Fig. 9, stacked upon a suitable conveyor tray 83 when positioned within an annealing furnace 84, may be coupled with one of the links of the conveyor chain 20 by means of a suitable detachable connecting member 86. The hand wheel 54 is rotated so as to retract the lock pin 53 and the control lever 43 is actuated so as to effect the engagement of one of the clutch members 37 with its companion driven clutch member 36. At this point it is to be understood that each of the combined clutch members 36 and 37 serves to independently operate two conveyor units 10. The hand wheel can then be operated to carry the lock pin into its projected position and the control lever 43 thus positively prevented from being returned to its neutral position. The cover 59 can now be opened and the upper starting button of the switch 57 actuated to close the circuit 29 including the motor 27. The sheets 81 are advanced from the furnace along the upper surfaces of the supporting channels 15 toward the

driving end of the apparatus. The motor is stopped when the sheets have been carried to their proper advanced position. It will of course be apparent that two sets of conveyor chains 20 may be operated simultaneously and two stacks of materials thus simultaneously withdrawn from the annealing furnace 84. The crank 75 is now turned so as to cause the elevation of the pipes 68 of the sprayer device 67 and when the proper elevation has been reached the valve 73 is opened. Water or other quenching medium passes through the perforations 69 in the pipes 68 and is directed upon the sheets 81. Water which passes through the screened floor 14 falls into the pit 12 and is carried off to a suitable drain 88 (Fig. 6) and when the sheets have been sufficiently quenched the pipes 68 are again lowered. A carrier mechanism such as the type disclosed in my co-pending application, Serial No. 126,168, filed July 31, 1926, may now be lowered into position and carried into engagement with the lower surfaces of the sheets 81 along the margins thereof and said sheets may be removed from their respective conveyor units.

What is claimed is:

1. In material treating apparatus, an endless horizontal material conveying means, a driving means therefor, means for spraying a fluid upon material associated with the conveying means, and means for vertically adjusting the position of the spraying means.
2. In material treating apparatus, conveying means for handling heated material, means for driving the conveying means, means for quenching material associated with the conveying means comprising a horizontally disposed sprayer, and means for vertically adjusting the position of the sprayer with respect to the material.
3. In material treating apparatus, a conveyor unit for handling heated materials including a horizontally disposed endless conveying means, and means for coupling the conveying means with heated materials, means for driving the conveying means, means for quenching material associated with the conveying means comprising an elongated fluid sprayer, and means for elevating the sprayer into operative position above the material and for lowering the sprayer to clear the material.
4. In material treating apparatus, a plurality of conveyor units for handling heated materials, each including endless conveying means, means for driving the conveying means, means for quenching material associated with the conveying means, and means operable to selectively cause the actuation of certain of the conveying means.
5. In material treating apparatus, a plurality of conveyor units for handling heated material, each including an endless conveying means, means for driving the conveying

means, material quenching means associated with each unit, means for adjustably positioning the quenching means with respect to the materials associated with each conveyor unit, and means operable to selectively cause the actuation of certain of the conveying means.

6. In material treating apparatus, a plurality of conveyor units, each including an endless horizontally disposed conveyor, means for driving the conveyor, means for supporting and guiding the conveyor in predetermined paths, means positioned at

each side of the conveyors for supporting material, quenching means associated with each conveyor unit including a horizontally disposed sprayer adapted to be vertically adjusted with respect to the materials associated with the conveyor units, means for simultaneously adjusting a plurality of the sprayers, and means operable to selectively cause the actuation of certain of the conveyors.

In witness whereof, I hereunto subscribe my name this 17th day of July A. D., 1926.

HANS HENRIK CHRISTIAN GRONDAHL.
